PLATE HOLDING MECHANISM FOR STEREOTYPE PRINTING PLATES

John Oldfield Crabtree, London, England, assignor to R. Hoe & Co., Inc., New York, N. Y., a corporation of New York

Application January 10, 1950, Serial No. 137,863
In Great Britain January 10, 1949

4 Claims. (Cl. 101—378)

1

This invention relates to mechanism for use in holding stereotype printing plates to the cylinders of rotary printing machines.

With the increase in operating speeds at which such machines are required to operate, an increasingly important factor affecting the ability of the normal plate-clamping mechanism to hold the plate in position is the centrifugal force which acts on the plate. This force, which is of course radial to the cylinder, tends to cause radial bulging of the plate.

The most normal type of clamping mechanism operates against the ends of the plate and imposes on the metal of the plate a compressional strain which, the greater it is made to secure the plate the more it tends in itself to assist the buckling action arising out of the centrifugal forces involved.

In another type of mechanism the plate is subjected at its ends to tension acting either along the length of the plate or around the curve of the plate. This mechanism results in subjecting the metal of the plate to a tensional strain which (so far as concerns the centrifugal force) is in a direction at right angles to that force and in consequence has to be considerable with the result that the metal tends to tear, for its nature is such that it is less adapted to resist tension than compression.

The present invention has for its object to provide a clamping mechanism in which the defects of the known mechanism are avoided.

Broadly stated the present invention consists in providing a printing cylinder with a number of plate-holding devices which are spaced apart over the plate-receiving area of the cylinder and each of which is so formed as in itself to grip the plate at its undersurface to hold the plate against movement radially outwards of the cylinder.

The various plate holding devices could take different forms in general each would be constructed to grip a plate either about an undercut or dovetail projection extending from the plate at its undersurface or within a dovetail undercut recess in the plate, the former arrangement being preferable.

It will be clear that with this arrangement the plate is held down to the cylinder at a number of places all within the boundary of the plate and at each of which the plate is virtually gripped to the cylinder. This result is achieved without relying on forces (whether compressional or tensional) acting along the plate from one end to the other and in addition the forces which the devices have to exert are in line with the radial forces to which they have to react.

2

By arranging a sufficient number of holding devices it is possible to preclude for all practical purposes any bulging of the plates between its held-down parts by reason of the inherent stiffness of the plate itself. Certain at least of these plate-holding devices can be arranged in themselves to hold the plate against endwise and/or circumferential movement on the cylinder although if desired other devices which play no part in holding the plate down to the cylinder in the radial sense could be used and these also would preferably cooperate with the undersurface of the plate.

The invention is illustrated in the accompanying drawings in which Figure 1 is a longitudinal sectional elevation showing part of the length of a printing cylinder incorporating this invention, and Figure 2 is an end sectional elevation of Figure 1, Figure 3 a detail sectional view and Figure 4 a diagrammatic development of a printing plate for use with this invention.

In the drawings, the reference 1 indicates a printing cylinder and the reference 2 the printing plate. For the purpose of the invention the plate 2 is formed at its under or concave surface with a series of clamping lugs which can be formed by undercut recesses or as shown by undercut projections 3 which are all within the boundary edges of the plate and which are distributed over the area of the plate. The lugs can be longitudinal of the plate but in the particular form shown in Figure 4, the lugs are formed by circumferential ribs extending from the undersurface of the plate, parallel with and preferably to the same extent as the usual internal ribs 4, as shown in Figure 1, the ribs 3 acting as do the ribs 4 to strengthen the plate and support it and also acting as clamping projections. These lugs could however be local, i. e. correspond only to short sections of the ribs.

Now, for the purpose of holding a plate to the cylinder the cylinder is provided with a series of projecting plate gripping devices disposed to engage the lugs 3 formed in undercut areas of the plate. In the particular arrangement as indicated by Figure 4, sixteen sets of gripping devices are used, these devices being indicated generally by reference 5.

These gripping devices 5 are arranged in longitudinal sets of four and each set comprises as shown in Figures 1 and 3 two components 6, 7. Both components are formed with undercut projections 8 to embrace the dovetailed lugs 3. One component 6 has a tubular extension 9 which houses a spring 10 which acts between the component 6 and a flange 11 on a sleeve 12 on which

the component 6 is slidable up to a limit stop 12'. The other end of this sleeve 12 is screw-threaded at 13 and engages an internally screw-threaded opening in the other component 7. The upper surface of the extension 9 and the corresponding surface of the component 7 are flush with the peripheral surface of the cylinder 1.

The various sleeves 12 are disposed (for each longitudinal set of four plate grips) on an operating rod 14 on which the sleeves can slide but not turn, the rod 14 and the bores of the sleeves being flattened or keyed for that purpose. The components 6 and 7 are flanged at 23 and are slidable in longitudinal grooves 15 by which they are held against rotation so that by turning the rod 14 the screw engagement between the sleeve 12 and the components 6 will cause the components 6 and 7 to be moved towards and away from one another: more particularly the turning of the rod 14 will cause all of the gripping devices 6, 7 mounted on it to move their projections 8 into and out of clamping cooperation with the various ribs 3, the pressure exerted being a resilient one by the action of the springs 10 which are compressed by the continued operation of the rod 14 after any pair of components 6 and 7 have engaged and gripped the respective dovetailed projections 3.

For the purpose of affording a longitudinal location of the plate one of the components 7 is fixed against longitudinal movement. The particular component selected would preferably be that nearest to one edge of the plate and in the drawings this component is marked with the additional reference X. This location is effected by a locating bar 16 having a lug 17 entering a notch in that component 7^x so that this component is fixed longitudinally with the result that when the rod 14 is turned the mating component 6 will be drawn towards the component 7^x and the plate will thus be locked in the longitudinal sense against the component 7^x.

To afford tolerance for the variations in the formation of the various ribs 3 on different plates, the other components 7 are also located by the locating bar 16 but with a small float or freedom by making the lug 17 a loose fit in the notch in the corresponding component 7.

In the particular case shown, the plate 2 extends over about 180° arc of the cylinder 1 and four rods 14 with their associated parts are employed.

While each rod 14 can be separately operated, it is preferred as shown in Figure 2 to arrange the various rods for one plate 2 to be operated together. This is effected by fitting each rod with a gear wheel 18 and inter-gearing the gears 18 by pinions 19 one of which can have a head 20 to receive an operating wrench.

As is indicated in Figure 1, the rods 14 can be extended to operate similar gripping components 6, 7 for a second plate the end of which is shown at 2'. Moreover, in the drawing only one diametral half of a cylinder is shown. The other half of the cylinder would of course be equipped similarly to the half shown.

In order to enable the sets of gripping components 6, 7 to be adjusted for printing plates of different sizes and also for obtaining register in multi-colour work, the location bars 16 can be adjusted longitudinally, the sets of components 6, 7 (which are free to slide along the rods 14) being caused to partake of the adjustment: such adjustment can be provided by slotting the bars 16 at 21, the slots receiving locking screws 22. A 75

fine adjustment mechanism (not shown) could be provided to adjust the bar.

I claim:

1. In combination a printing cylinder, a curved stereotype printing plate having distributed over its concave surface a series of undercut projections, arranged in groups, a corresponding series of gripping devices arranged in corresponding groups, each gripping device comprising a first component constituting an abutment and a second component to clamp a projection between them, means to locate the first component of a gripping device of each group to be engaged by a projection, and to allow limited free movement of the first component of each other device of the group, means to operate the second components of each group to move them relatively into and out of embracing engagement with their respective projections, the said operating means operating on the second component of each device through a resilient component.

2. In combination a printing cylinder, a curved stereotype printing plate having distributed over its concave surface a series of transverse undercut projections arranged in groups extending longitudinally of the plate, a corresponding series of gripping devices mounted on the cylinder and arranged in corresponding longitudinal groups, each device comprising two gripping components, a first component constituting an abutment and a second component to clamp a projection between them, means to locate longitudinally a first component of one device of each group and to locate with limited freedom the first gripping components of the other devices of the group, an operating component for the devices of each group adapted to move the second components into embracing engagement with their respective projections, and spring means associating the second gripping components of each group to its operating component.

3. In combination a printing cylinder, a curved stereotype printing plate having distributed over its concave surface a series of undercut projections arranged in groups, a corresponding series of gripping devices arranged in corresponding groups, each gripping device comprising two components to embrace a projection between them, means to operate the components of each group simultaneously to move into and out of embracing engagement with the projections, means to locate one component of a gripping device of each group and to allow limited free movement of one component of each other device of the group, means to adjust the locating means, means to operate the components of each group to move them relatively into and out of embracing engagement with their respective projections, the said operating means operating on the second component of each device through a resilient component.

4. In combination a printing cylinder, a curved stereotype printing plate having distributed over its concave surface a series of transverse undercut projections arranged in groups extending longitudinally of the plate, a corresponding series of gripping devices mounted on the cylinder and arranged in corresponding longitudinal groups, each device comprising two gripping components, means to locate longitudinally one component of one device of each group, and to locate with limited freedom the corresponding gripping components of the other devices of the group, means to adjust the locating means, an operating component for the devices of each

group, the said component operating to move the two components into embracing engagement with their respective projection, and spring means associating the second gripping components of each group to its operating component.

JOHN OLDFIELD CRABTREE.
